(57) **CLAIM**

The ornamental design for a radio/CD charger, as shown and described.

DESCRIPTION

FIG. 1 is a front perspective view of the radio/CD charger of the present invention;

FIG. 2 is a back perspective view;

FIG. 3 is a front view;

FIG. 4 is a rear view;

FIG. 5 is a top view;

FIG. 6 is a bottom view;

FIG. 7 is a left end view; and,

FIG. 8 is a right end view.
